US0D1102372S

(12) **United States Design Patent** (10) **Patent No.:** **US D1,102,372 S**
Underhill et al. (45) **Date of Patent:** **** Nov. 18, 2025**

(54) **JUMP STARTING DEVICE**

(71) Applicant: **THE NOCO COMPANY**, Glenwillow, OH (US)

(72) Inventors: **Derek Michael Underhill**, Tempe, AZ (US); **Jonathan Lewis Nook**, Gates Mills, OH (US)

(73) Assignee: **The Noco Company**, Glenwillow, OH (US)

(**) Term: **15 Years**

(21) Appl. No.: **29/864,884**

(22) Filed: **Jun. 24, 2022**

Related U.S. Application Data

(62) Division of application No. 29/759,817, filed on Nov. 25, 2020, now Pat. No. Des. 981,953.

Primary Examiner — Christy Nemeth*(74) Attorney, Agent, or Firm* — Jones Day(57) **CLAIM**

The ornamental design for a jump starting device, as shown and described.

DESCRIPTION

FIG. 1 is a perspective view of a jump starting device of our new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The broken lines in the drawings depict portions of the jump starting device that form no part of the claimed design.

1 Claim, 7 Drawing Sheets
